(57) **CLAIM**

The ornamental design for a cover holder for cat litter box, as shown and described.

DESCRIPTION

FIG. 1 is a perspective view of a cover holder for cat litter box showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1; and,
FIG. 10 is an enlarged view of portion 10 shown in FIG. 2. The dashed broken lines illustrate portions of the cover holder for cat litter box that form no part of the claimed design. The two-dash broken lines illustrate the boundary of enlarged views that form no part of the claimed design. The dot-dash broken lines represent the boundary of the claimed design, and form no part thereof.

1 Claim, 10 Drawing Sheets
